UNITED STATES PATENT OFFICE.

ASA LEROY BURKE, OF STRATFORD, ONTARIO, CANADA.

WASHING-MACHINE.

SPECIFICATION forming part of Letters Patent No. 371,546, dated October 18, 1887.

Application filed July 20, 1887. Serial No. 244,806. (No model.) Patented in Canada August 17, 1885, No. 2,255.

To all whom it may concern:

Be it known that I, ASA LEROY BURKE, a citizen of Canada, residing at Stratford, in the Province of Ontario and Dominion of Canada, have invented certain new and useful Improvements in Washing-Machines, (for which I have obtained Letters Patent in Canada, dated August 17, 1885, No. 2,255;) and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to improvements in washing-machines for which Letters Patent were granted to me in Canada August 17, 1885, No. 2,255; and it has for its object to simplify and cheapen and otherwise improve the construction and render more efficient in operation and durable this class of devices.

To these ends and to such others as the invention may relate the same consists in the peculiar construction and in the novel combination, arrangement, and adaptation of parts, all as more fully hereinafter described, shown in the drawings, and then specifically defined in the claim.

In the accompanying drawings, Figure 1 is a side view with parts broken away. Fig. 2 is a central longitudinal vertical section. Fig. 3 is a perspective with the rubber removed from the suds-box and in the position it will assume after the washing operation is completed and the parts have been left to drain. Fig. 4 is a longitudinal vertical section through the suds-box on the line xx of Fig. 3, with part of the slats that form the rubbing-surface removed. Fig. 5 is an end view with parts broken away. Fig. 6 is a bottom plan of the rubber with some of the slats forming the rubbing-surface removed.

Referring, now, to the details of the drawings, A represents my suds-box, composed of the two rectangular sides B, upon the inner faces of which, upon the segment of a circle, I form the grooves a , in which is first placed the sheet-metal (preferably zinc) bottom C, which, it will be noticed, is very thin compared with the width of the groove, so that when said bottom is in place within the grooves

upon the adjacent faces of the sides a groove, a' , is left for the reception of the ends of the slats D, which form the rubbing-surface of the suds-box. At one end the sides B are recessed upon their top edges, and in this recess is secured by suitable means a strip, E, to the top edge of which, near the center, is secured the strip or cleat, b , the object of which will be explained farther on. At this end of the suds-box, and within the groove a of the sides thereof, is secured the strip c , which abuts against the under surface of the strip E, and thus closes the grooves at this end; but this strip c may sometimes be omitted and the slats D run farther up and abut against the under side of the strip E.

The slats D, which form the rubbing-surface of the suds-box, are each of substantially the form shown removed in Fig. 4, and are removably inserted in the grooves a of the sides above the bottom C, and are slipped in from the end A', where the grooves terminate in substantially horizontal portions over the bottom C, and are slipped along in the grooves until the rubbing-surface is completed, the first slat put in abutting against the strip c at the opposite end, which forms a stop for the slat. When the slats are all in, the vertical strip F, which carries the wringer, as herein-after described, is secured in place within a recess formed in the end of the sides for its reception, as shown in the drawings, thus closing the ends of the grooves and preventing displacement of the slats; but if at any time it should be desired to remove any or all of the slats for repairs or other purposes the removal of the strip F opens the ends of the grooves, when the slats may be readily removed.

The box is supported upon suitable legs, d , and braced upon its under side by cleats e , preferably let into recesses or sockets e' upon the under side of the sides B, and the latter one, e' , serving an additional function, which will be hereinafter described.

In the top edges of the sides of the suds-box are suitable bearings, f , in which are journaled the ends g of the shaft G, which passes through elongated slots h , formed in the standards H, said standards being formed below said slots with shoulders i , against which bear the upper edges of the sides I of the rubber. The sides I of the rubber are substantially seg-

mental in form, and are secured to the legs of the standards, as shown. The under sides of the sides of the rubber are formed with recesses *j*, in which recesses and against said shoulders are secured the slats *k*, which form the bottom of the rubber. These slats may be of any suitable form to constitute an efficient rubbing-surface. It will be noticed that by this peculiar construction I provide a rubber

10 which is exceedingly strong, and is not liable to break, as the strain on the bottom is provided for and distributed between the shoulders *j* on the rubber sides and the shoulders *i* of the standards *H*.

15 Between the standards the shaft *G* is enlarged or formed with shoulders to prevent endwise displacement thereof. The upper ends of these standards are enlarged, as shown at *l*, to form bearings for the shaft *K*, which is 20 passed therethrough and through suitable holes in the arms *L*, and there secured by suitable pins. The outer ends of these arms are connected by a suitable operating-handle, *L'*, while the opposite ends are sleeved upon the shaft 25 *M*, connecting the upper ends of the links *N*, the lower ends of which are pivoted to lugs *n*, suitably secured to the sides of the suds-box.

30 To prevent end displacement of the shaft *G* in its bearings in the suds-box, I secure to the sides of the box against the ends of the bearing suitable pieces, *m*, and to allow of the ready removal of the rubber and its attached parts I pivot to the top edges of the sides of the suds-box the buttons *l'*, which extend across the 35 bearings therein and prevent vertical displacement of the ends *g* of the shaft *G*, but when turned around, as shown in Fig. 3, leave the parts free to be removed, as shown in the same figure.

40 The strip *F* carries a wringer, *O*, as shown. Beneath the wringer end of the machine I arrange a tray or clothes-receptacle, *P*, adapted to receive the clothes as they are taken from the machine, and in order that this may be out 45 of the way when not in use I construct it as follows: To the under side thereof, at the rear end, I attach a strip, *s*, of the same thickness as the cleat *e'*, and to the underside of the strip

s, parallel with the bottom of the clothes-receptacle, I secure a thin strip, *t*, which projects 50 a sufficient distance beyond the edge of the piece *s*, so that when the clothes-receptacle is extended it will engage the under side of the cleat *e'*, and firmly hold the receptacle in place. The sliding of the receptacle backward disengages this catch from the cleat *e'*.

The suds-box is provided at one side with an opening, *w*, through which the water may be removed when necessary, which opening may be closed by a faucet, plug, or other suitable means.

The operation is apparent, and a description thereof is unnecessary; but one point needs to be called to attention. By the construction above described, after the clothes have been 65 washed, the parts can be readily made to assume the position shown in Fig. 3, when the rubber is in a position to drain, so that the drippings will fall back into the suds-box and not onto the floor, the cleat *b* serving to hold 70 the rubber in position.

Having thus described my invention, what I claim as new, and desire to secure by Letters Patent, is—

In a washing-machine, the combination, with 75 the sides *B*, formed upon their adjacent faces with segmental grooves *a*, terminating at one end in horizontal portions, as shown, and recessed at each end upon their upper edges, the strip *E*, secured in the recesses at one end, the strip *e*, fitting in said grooves and abutting against the under side of said strip, the metal bottom *C*, seated in said grooves, the slats *D*, removably inserted in said grooves and resting directly upon said bottom, and the strip *F*, secured in the recesses at the opposite end of said 80 sides and closing the horizontal portion of said grooves, substantially as and for the purpose described.

In testimony whereof I affix my signature in 90 presence of two witnesses.

ASA LEROY BURKE.
